VENTILATING WINDOW MECHANISM

Albert P. Ball, Detroit, Mich., assignor, by mesne assignments, to Automobile Ventilation, Inc., Detroit, Mich., a corporation of Michigan

Application June 20, 1935, Serial No. 27,505

9 Claims. (Cl. 296—44)

This invention relates to ventilating windows for vehicle bodies, particularly automobile bodies of the type wherein a window opening in the side or door of the body is provided with a window glass adapted to be raised and lowered therein and also adjusted into position to provide a ventilating slot or opening at one upright edge of the glass.

An object of the present invention is to provide a ventilating window of the foregoing type wherein the structure, including the window operating mechanism, may be considerably improved and simplified and thereby rendered materially more economical to manufacture.

Another object of the invention is to provide an improved vehicle door or side window having a window glass mounted to move vertically or substantially so in a straight line path into fully closed position, and wherein the glass is adapted to be tilted or oscillated angularly after attaining said fully closed position, within the window opening to produce a ventilating slot or opening at one upright edge of the glass, preferably the forward edge, whereby air may be exhausted, during the forward travel of the vehicle, from the interior of the body through the ventilating slot or opening when the glass is in its tilted or ventilating position.

A further object of the invention is to provide improved window regulator mechanism connected to the lower edge of the glass of a ventilating window of the above mentioned type, said mechanism being operable to raise and lower the glass and also to tilt the glass, when raised, into and out of position to provide the ventilating slot.

The above and other objects and advantages of the invention will appear from the following description and appended claims when considered in connection with the accompanying drawings forming a part of this specification:

In said drawings:

Fig. 1 is a fragmentary elevation, partly in section and partly broken away, illustrating a front door of a vehicle body embodying the invention and showing the position of the operating mechanism when the glass is in ventilating position.

Fig. 2 is horizontal section taken substantially along the line 2—2 of Fig. 1.

Fig. 3 is a horizontal section taken substantially along the line 3—3 of Fig. 1.

Fig. 4 is a vertical section taken substantially along the line 4—4 of Fig. 1, looking in the direction of the arrows.

Fig. 5 is a vertical section taken substantially

along the line 5—5 of Fig. 1, in the direction of the arrows; and

Fig. 6 is fragmentary elevation, partly in section, of the door of Fig. 1, showing the position of the operating mechanism when the glass is closed or in non-ventilating position.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

Referring particularly to the drawings there is shown, by way of example, the front door of a vehicle, such as a motor vehicle, having a window glass mounted therein and adapted to be elevated by a regulator mechanism into and out of position within the window opening of the door, and to be shifted or tilted downwardly by said mechanism when in fully closed position to provide a ventilating slot or opening between one upright edge of the glass and the adjacent door pillar. The regulator mechanism is thus operative to shift the window glass into open or closed positions and to tilt or oscillate the glass angularly in its plane in a downward direction when in fully closed position to produce a ventilating slot at one upright edge of the glass and, prior to lowering the glass, to tilt or oscillate the glass angularly in its plane in an upward direction to close the ventilating slot.

As shown in the drawings, the door comprises a front pillar 10 and a rear pillar 11 connected at their upper ends by the usual header 12. The door also comprises an outer metal panel 13 and an inner metal panel 14 provided with a garnish molding 14a, these panels forming a well within the door for receiving the window glass when lowered. Mounted in the front pillar 10 is a 45 felted glass channel member 15 and in the rear pillar 11 there is mounted a felted glass channel member 17, there being a connecting channel member 16 located in the header 12. These cooperating felted channel members provide seats 50 and guides for the upright and top edges of the window glass 18. The rear or inner upright edge of the glass is preferably cut so as to extend at an angle to its bottom edge 18a, as at 18b, which angle is herein shown as greater than a right angle 55

angle. The top edge of the glass is curved at 18c to conform to the curvature of the channel members 15 and 16 and likewise to conform to the shape or contour of the window reveal. Toward 5 its lower forward edge the glass is cut at 18d to provide a straight guiding edge and terminates in a lower forward rounded corner portion 18e. The straight angular edge 18b permits the glass to be tilted or oscillated angularly in its plane 10 when in fully raised position in its window opening as shown in Fig. 1, in which position a ventilating slot or opening 40 is provided at the forward upright edge of the glass. The front runway or channel 15 is extended downwardly in a 15 substantially vertical plane to provide a relatively shallow channel portion 19. The rear channel 17 is extended downwardly to provide an angularly disposed or inclined relatively shallow channel portion 20 which, as shown in Fig. 6, extends in 20 an inclined plane which is substantially parallel to the inclined rear edge 18b of the glass. The channel extensions 19 and 20 together serve to guide the window glass during the lower portion 25 of its travel. The rear channel 20 guides the rear edge of the glass while being lowered or raised in a path which clears the door handle operating shaft 21.

The window regulator for raising and lowering the glass and for tilting or oscillating it angularly in its plane when in raised position may be of any suitable construction. In the present embodiment, by way of example, the regulator comprises a mounting plate 22 secured in any suitable manner, as by screws 22a, to a lock board 30 on the inside of the door well. The plate 22 carries a pair of intermeshing gears 23 and 24 which are journaled on the plate by means of pivots 23a and 24a, respectively. The gears are rotated by means of a pinion 25 operated by a handle 26. Secured to the pivot 23a is a swinging arm 27 and secured to the pivot 24a is another swinging arm 28, these arms being adapted to be swung in opposite directions by rotation of the gears. Secured to the outer end of the arm 27 is a stud or button-like device 29 having a shank riveted to the end of the arm (Fig. 4). To the outer end of the arm 28 there is secured another stud or button-like device 30 having its shank riveted to the end of the arm. Secured to the lower normally horizontally disposed edge 18a of the glass 18 is a glass retainer member including a felted channel 31 having adjacent one end a plate 32 preferably spot welded to one face of the channel (see Fig. 4) and having a forwardly flanged wall 55 providing with the bottom of the channel 31 a runway or slot 33 for the stud 29. Adjacent the opposite or inner end of the felted channel 31 there is provided a depending plate 34 secured to the channel preferably by spot welding (Fig. 60 5). The lower end of the plate 34 is flanged at 34a, this flange cooperating with a similar flange 35 formed on a small plate preferably spot welded to the face of the plate 34 to provide therebetween a runway or slot shown as a whole at 36 to receive 65 and guide the button-like device or stud 30. It is to be noted that the runways 33 and 36 have constricted necks forming upper and lower tapered faces engaged by the tapered studs 29 and 30, and 70 that the members 31 and 32 of one runway and the corresponding members 34a and 35 of the other runway, have outwardly flared bearing portions which are engaged by conical spring-pressed washers (see Fig. 4). From this construction it 75 will be seen that when the arms 27 and 28 are

swung relatively to each other, the studs 29 and 30 will slide in the runways 33 and 36.

It is to be noted that the runways or retainer members 33 and 36 are in the present embodiment angularly related with respect to one another and that each of the runways has its own angularly related portions. The runway or retainer member 33 has a normally horizontally disposed straight guideway portion 33a and an angularly disposed and curved portion 33b, these portions 10 33a and 33b merging and cooperating as one continuous guideway for the reception and travel of the stud 29. The runway or retainer member 36 also has angularly related portions, the forward or idle portion 36a being angularly disposed with 15 respect to the straight normally horizontally disposed portion 36b of the guideway, the portions 36a and 36b merging and being co-extensive with one another for the reception and travel of the 20 arm carried stud 30. It is to be understood that when the stud 30 travels in the angular portion 36a through the operation of arm 28, such travel does not affect the position of the glass 18 other than to hold one side thereof in fully raised position or substantially so. In other words, the portion 36a is the idle portion of the rear or inner 25 guideway 36.

Referring to Fig. 6, the operating mechanism is shown in full lines with the glass in fully closed or non-ventilating position. It will be seen that the 30 studs 29 and 30 are located at the juncture of the horizontal and angularly disposed portions of the guideways 33 and 36, respectively. The glass has been moved into this position from its lowered position by rotation, in a counterclockwise direction, of the handle 26 which, through the pinion 25 and gears 23 and 24, has caused the arms 27 and 28 to swing upwardly and inwardly toward one another, with their studs 29 and 30 travelling in the normally horizontal portions 33a and 36b, respectively, of the front and rear runway. If it is desired to produce the ventilating slot or opening 40 (Fig. 1) it is merely necessary to turn the handle 26 farther in a counter-clockwise direction, during which turning or rotation of the handle the 40 stud 29 will travel upwardly in the portion 33b of the runway while at the same time the stud 30 is travelling upwardly in the idle portion 36a of the rear runway, this travel of the stud 29 serving to tilt or oscillate the glass 18 in its plane about an 45 imaginary axis from the position from which it is shown in Fig. 6 to its position of Fig. 1. In the latter position, it will be seen that the rear edge 18b of the glass is seated against the felt-lined channel 17 in the rear door pillar. When it is 50 desired to lower the glass 18 into its well in the door, the handle 26 is rotated in the opposite or clockwise direction which causes the arms 27 and 28 to move outwardly and downwardly away from one another, the initial travel of the studs 29 and 30 being in the portions 33b and 36a of the runways 33 and 36, respectively. While the stud 29 is travelling through the portion 33b the glass 18 is tilted or oscillated upwardly into closed position (see Fig. 6) while similar travel of the stud 30 55 in the idle portion 36a of the rear runway merely serves to support the glass during its tilting or oscillating movement. The studs 29 and 30 are now at the junctions of the angularly related portions of the runways. Further clockwise rotation 60 of the handle causes the arms 27 and 28 to swing farther outwardly and downwardly, their respective studs 29 and 30 travelling in the horizontal portions 33a and 36b of the runways and lowering 65 the glass, while remaining in its normal horizon- 70 75

tal position, downwardly into the well. During its downward movement the vertical portion 18d of the front edge of the glass is guided by the front felted channel 19 whereas the upper corner of the 5 rear edge of the glass contacts the felted channel 17 during its downward movement, the glass being thus guided against tilting during its descent into the well.

It if it is again desired to close the window opening, the handle 26 is rotated in a counter-clockwise direction until the glass assumes its position of Fig. 6, with the window opening entirely closed. During the travel of the glass upwardly and downwardly to close and open the 10 window opening, the lower edge of the glass is maintained in its normal or horizontal position. Upon reaching its uppermost or closed position, further counterclockwise rotation of the handle tilts or oscillates the glass downwardly at its forward edge to create the ventilating slot 40, as previously described. It will be seen that it is impossible to tilt the glass into ventilating position except when it is in its uppermost or closed position. Moreover, it is impossible to lower the glass when 15 in its tilted position, it being necessary to close the ventilating slot and return the glass to its normal horizontal position before it can be lowered into the well.

I claim:

30 1. In a vehicle body having a side window opening and a sliding window glass mounted therein and adapted to close said opening, a window regulator including swinging arms for moving the glass into fully elevated position, and means carried by 35 said glass cooperating with said regulator arms for tilting the glass in its plane from its closed position into position to provide a ventilating slot at one upright edge of the glass upon further operation of said regulator in its closing direction.

40 2. In a vehicle body having a window opening and a sliding window glass mounted therein and adapted to close said opening, a window regulator including a pair of swinging arms for moving the glass into fully elevated position, and means secured to the lower edge of the glass and cooperating 45 with said regulator arms for tilting the glass in its plane from its closed position into position to provide a ventilating slot at the forward edge of the glass upon further operation of said regulator in its closing direction.

50 3. The combination in a vehicle body of a window frame having a window opening and a well therebelow, a window glass, regulator mechanism for moving the glass into and out of said opening and said well from lowered position to fully closed position and vice versa, means for guiding opposite upright side edges of the glass, and means carried by the glass engaged by and cooperating with a part of said mechanism for oscillating the 55 glass in its plane only after reaching fully raised position to provide a ventilating opening at one upright edge of the glass.

4. The combination in a vehicle body of a window frame having a window opening and a well therebelow, a window glass, regulator mechanism for moving the glass into and out of said opening and said well, means for guiding opposite upright side edges of the glass, and means on the glass engaged by and cooperating with a part of said mechanism for oscillating the glass 60 in its plane when in fully closed position to provide a ventilating opening at the forward upright edge of the glass.

5. In a vehicle body having a window opening,

a rearwardly curved relatively shallow front glass channel, and a rear relatively deep glass channel; a window glass having its rear upright edge inclined relative to the lower edge thereof at an angle greater than ninety degrees for entirely 5 closing said opening when in elevated position, means for sequentially oscillating the glass in its plane within said opening when in closed position to produce and then close a ventilating slot between the forward edge of the glass and the 10 shallow glass channel while varying the depth of penetration of the rear edge in said deep glass channel, and means for lowering the glass with the glass in non-ventilating position.

6. Regulator mechanism for a vehicle body having a side window opening and a window glass adapted to close said opening, retainer means carried by the lower edge of said glass, said regulator mechanism comprising means connected to said retainer means for raising and lowering the 20 glass in a substantially straight-line path while maintaining the upright edges of the glass in non-ventilating position and for tilting said glass in its plane into its ventilating position wherein a 25 ventilating slot is provided at one upright edge of the glass.

7. Regulator mechanism for a vehicle body having a side window opening and a window glass adapted to close said opening, retainer members carried by the lower edge of said glass, said regulator mechanism including a pair of swinging arms connected to said retainer members for raising and lowering the glass in a substantially straight-line path while maintaining the forward edge thereof in non-ventilating position and for 30 tilting said glass in its plane when in raised position to provide a ventilating slot at the forward 35 upright edge of the glass.

8. In a vehicle body having a side window opening and a sliding window glass mounted therein and adapted to close said opening, a rail mounted upon the lower edge of the glass, cam tracks supported by and depending from said rail adjacent its opposite ends, regulator mechanism comprising a pair of swinging arms, means carried 45 by one end of each of said arms engaging said cam tracks, gearing connected with the opposite ends of said arms for swinging the same, and manually controlled means for operating said gearing for raising and lowering said glass to 50 close and open said window opening and to tilt the glass substantially in its plane when in elevated position to produce a ventilating slot of variable length and width at the forward edge of the glass.

9. In a vehicle body having a side window opening and a slidable window glass mounted therein and adapted to close said opening, a metal retainer member mounted upon the lower edge of said glass, plates depending from said retainer member 60 and carried thereby, guideways formed in said plates, window regulator mechanism comprising a pair of swinging arms having at their outer ends means engaging said guideways, intermeshed gears located at the opposite ends of said arms for 65 swinging the same, and a manually controlled pinion meshing with one of said gears for driving the same whereby to raise and lower the window glass, said glass travelling upwardly while remaining in horizontal position and being tilted in its 70 plane upon reaching its fully elevated position to produce a ventilating slot of variable length and width at the forward upright edge of the glass.

ALBERT P. BALL.
